US00D947428S

(12) **United States Design Patent** (10) Patent No.: **US D947,428 S**
(45) Date of Patent: **** Mar. 29, 2022**

(54) **HEAD LAMP FOR AUTOMOBILE**

(71) Applicants: **HYUNDAI MOTOR COMPANY**, Seoul (KR); **KIA MOTORS CORPORATION**, Seoul (KR)

(72) Inventors: **Jung-Taik Hur**, Gyeonggi-do (KR); **Oh-Young Kwon**, Suwon-si (KR); **Hyeong-Seon Kim**, Anyang-si (KR); **Hwi-Eon Kim**, Hwaseong-si (KR)

(73) Assignees: **Hyundai Motor Company**, Seoul (KR); **Kia Motors Corporation**, Seoul (KR)

(**) Term: **15 Years**

(21) Appl. No.: **35/510,794**

(22) Filed: **Jul. 28, 2020**

(80) **Hague Agreement Data**

Int. Filing Date: **Jul. 28, 2020**

Int. Reg. No.: **DM/211142**

Int. Reg. Date: **Jul. 28, 2020**

Int. Reg. Pub. Date: **Nov. 20, 2020**

(30) **Foreign Application Priority Data**

Jan. 30, 2020 (KR) 30-2020-0004125

(57) **CLAIM**

The ornamental design for a head lamp for automobile, as shown and described.

DESCRIPTION

1. Head lamp for automobile

1.1 : Perspective

1.2 : Front

1.3 : Back

1.4 : Left

1.5 : Right

1.6 : Top

1.7 : Bottom

Reproduction 1.1 is a perspective view of a head lamp for automobile showing our new design; reproduction 1.2 is a front elevation view thereof; reproduction 1.3 is a back elevation view thereof; reproduction 1.4 is a left side elevation view thereof; reproduction 1.5 is a right side elevation view thereof; reproduction 1.6 is a top plan view thereof; and reproduction 1.7 is a bottom plan view thereof.

1 Claim, 7 Drawing Sheets
